DESIGN FOR A BOTTLE

Paul C. Delaize, New York, N. Y.

Application February 7, 1935, Serial No. 55,290

Term of patent 3½ years

To all whom it may concern:

Be it known that I, Paul C. Delaize, a citizen of France, residing in New York, in the county and State of New York, have invented a new, original, and ornamental Design for a Bottle, of which the following is a specification, reference being had to the accompanying drawing, forming part thereof.

In the drawing—

Figure 1 is a top plan view of a bottle embodying my invention;

Figure 2 is a front elevation of the same;

Figure 3 is a side elevation of the same; and
Figure 4 is a transverse cross section taken substantially on line 4—4 of Figure 2.

I claim:

The ornamental design for a bottle as shown.

PAUL C. DELAIZE.
